UNITED STATES PATENT OFFICE.

CHARLES T. BURLIN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

PRESSER FOR FLIERS.

1,103,654.

Specification of Letters Patent. Patented July 14, 1914.

Application filed April 7, 1914. Serial No. 830,101.

To all whom it may concern:

Be it known that I, CHARLES T. BURLIN, a citizen of the United States, residing at Whitinsville, in the county of Worcester 5 and State of Massachusetts, have invented the following described Improvements in Pressers for Fliers.

The invention relates to an improved construction of the centrifugal pressers used 10 on the fliers of roving frames, and provides a structure which can be produced at a less cost than heretofore, being otherwise the same in function and serviceability as the style of presser now in use. The new 15 presser may be made entirely from a flat sheet metal blank, in a few simple operations in suitable dies.

In the accompanying drawings: Figure 1 shows a flier such as used on roving frames 20 and having a presser constructed in accordance with this invention mounted on one of the legs thereof. Fig. 2 is a cross-section of Fig. 1, on line 2—2. Fig. 3 is a similar view, on line 3—3. Fig. 4 is a partial section 25 through the lower bearing of the presser on the flier leg. Fig. 5 is a modified form of tang, illustrated as though a section on line 3—3 of Fig. 1; and Fig. 6 represents the flat blank from which the presser is 30 formed.

The flier appearing in Fig. 1 may be of any suitable construction and forms no part 35 of the present invention. It is illustrated as reinforced by the girdle ring 1 joining the extremities of its two legs to keep them from spreading. The leg 2 is hollow and slotted, as usual, so that the yarn may be introduced into the interior thereof and pass through the same to the tang of the 40 presser in the usual way. For convenience of reference herein, the presser may be assumed to be composed of two parts, namely, a body and a tang portion, the body being the part that extends parallel with the flier 45 leg 2 and is provided with upper and lower bearings thereon, and the tang portion being the horizontal part which carries the presser pad at its end.

According to this invention, the blank 50 formed as in Fig. 6, is stamped or punched with holes or slots 3, 4 and 5, in substantially the arrangement shown. The hole 4 in the process of punching is drawn into a boss 6, of a suitable internal diameter to fit 55 loosely over the end of the presser leg 2, as

shown in Fig. 4, and the hole 5 is countersunk and its edge rounded so as to provide a smooth passage for the yarn therethrough. The slot 3 is formed near the end of a lateral arm 7 at the top of the blank and is of such width as will accommodate within it the lug 8 that has previously been punched out of the wall forming the hollow flier leg 2. The length of this slot is sufficient to accommodate such range of oscillatory movement as may be required for the presser when finished. The lateral slotted extension 7 at the head of the blank is curled about an axis parallel to the main body of the presser and so as to surround the upper part of the flier leg 2, with the lug 8 thereon penetrating the slot 3, thereby forming the upper bearing for the presser. This bearing, as will be observed, also holds the presser longitudinally in position on the leg. The lower end of the sheet metal blank which contains the bossed bearing 4, is bent transversely to the body of the presser, substantially at right angles thereto, so that it will embrace the end of the flier leg, as 80 shown in Fig. 4, when the slot 3 of the upper bearing is engaged by the lug 8, and the tang 9 is twisted so as to bring the entrance slit 10 in the yarn hole 5, on the upper side of the presser pad 11. It is best to twist the tang in a direction which conforms to the direction in which the yarn is wrapped around it, so that thereby a smooth helical surface will be provided for the yarn to move upon toward the hole or eye in the 90 pad. For this purpose the tang may be twisted a quarter or more turns, according as preferred, it being evident that the entrance slit 10 should be on the upper side of the pad and that the blank should be 95 punched accordingly.

In Figs. 1 and 3 the tang is shown as twisted three-quarters of a revolution, whereas in Fig. 5, it is shown twisted but a quarter of a revolution, and it will be understood that its edges are in any event well rounded, so that it will provide a proper surface for the yarn to move on, irrespective of the number of turns the operative may wrap the latter upon it, or, indeed, the direction of such wrapping.

The body of the blank is folded one or several times on parallel lines, as indicated at 12 in Fig. 6, the folding preferably being done in alternate directions so as to pro- 110

vide a number of layers, 15, 14 and 16, as illustrated in Figs. 3 and 5, all these layers being compactly pressed together as shown, and desirably curved slightly so as to project no more than necessary from the leg 2. It will be evident that the necessary clearance of the presser body from the leg is determined by the location of the bossed bearing 6 in the lower bent over portion and 10 by the offset of the neck 17 at the top of the body. When the presser is mounted on the flier leg, the mass of the folded body is sufficient to counterbalance that of the pad and tang, so that the latter are pressed inwardly toward the bobbin, as the result of 15 the centrifugal action. The proportions of the blank, as well as the thickness of the metal, are adjusted accordingly and obviously may be designed to give any desired 20 effect. A larger or smaller number of folds may be incorporated in the body, as desired, and the portion to be folded is desirably separated from the slotted part 7, by an open space 18, forming the neck 17, and the 25 said portion to be folded also terminates above the bent over part 19, which joins the body to the tang.

I claim:

1. A sheet metal presser for fliers, consisting of a body folded in two or more layers, with integral end portions bent to form upper and lower presser bearings and an extension of the lower bent portion forming a tang and having a pad thereon.
2. A presser formed of a sheet metal blank, with the lower end bent over transversely to the presser body and punched with a bossed aperture forming a bearing

for the presser upon the flier, a tang extending integrally from such bent over portion 40 and an integral pad on the end of the tang.

3. A presser having a body part formed of a sheet metal blank folded on itself, with the upper and lower parts of such blank bent to form upper and lower presser bearings, the lower part having an integral extension forming a pad and tang, and said extension being twisted one or more quarter turns with reference to the said lower bearing. 50

4. A presser formed of a sheet metal blank, having a body composed of folded layers of the sheet metal blank, an upper bearing formed in an integral curled portion extending from the top of the blank, 55 and a tang and pad formed in an integral bent over and twisted portion extending from the lower end of the blank, said latter portion having an aperture with a bossed margin forming a lower presser bearing in 60 alinement with the said upper bearing.

5. A presser formed of a sheet metal blank folded in two or more layers to form the body and provided with upper and lower bearings and a bent over tang portion at 65 the lower bearing, the latter portion being angular in cross section and twisted with reference to the bearing, and a pad at the end of said portion.

In testimony whereof, I have signed this 70 specification in the presence of two witnesses.

CHARLES T. BURLIN.
